COAT AND TROUSERS HANGER

Walter Harold Batts, Grand Rapids, Mich.

Application December 21, 1938, Serial No. 247,066

3 Claims. (Cl. 223—88)

This invention relates generally to garment hangers and more particularly to a type of hanger adapted to receive the coat and trousers of a suit whereby the weight of the coat aids in preventing the trousers from slipping and thus becoming wrinkled.

The principal object of the invention is to provide a suitable covering for a wire frame so that the bottom of said covering will contact the trousers on the hanger when a coat is placed over the covering to prevent them from slipping.

Another object of the invention is to provide a covering adapted to be folded over the wire frame and yet permit the covering to be moved thereon.

A still further object is the provision of scored portions in the covering so that when a coat is placed thereover these portions will provide a substantially round surface on which the shoulders of the coat may rest to prevent the wrinkling thereof.

Other objects and purposes will appear as the description proceeds.

To the accomplishment of the foregoing and related ends said invention, then, consists of the means hereinafter fully described and particularly pointed out in the claims.

The annexed drawings and following description set forth in detail certain means for carrying out my invention, said means constituting, however, but one of various ways in which the principle of the invention may be used.

In said annexed drawings, wherein like reference numerals refer to like parts throughout the various views:

Fig. 1 is an elevational view of the wire frame and the covering therefor, which covering is shown in its raised position.

Fig. 2 is a front elevational view of my device showing the position of the covering when the coat and trousers are in position thereon.

Fig. 3 is a plan view of the cardboard covering as it appears laid out before being folded over the wire frame.

Fig. 4 is a fragmentary perspective view of the covering in a partially folded condition.

Fig. 5 is a vertical section through the hanger with the covering in position shown in Fig. 2.

Fig. 6 discloses one way in which the hooked member of the wire frame may be formed and,

Fig. 7 is a modification of the hooked member shown in Fig. 6.

Referring now more particularly to the drawings and more especially to Fig. 1, the frame member is composed of the two diverging shoul-

der portions 1 and 2 which meet at their upper ends and form the hook member 3 either by twisting these portions together as at 4 in Fig. 7 or by merely pinching the two portions together by means of the piece 5 as shown in Fig. 6. This is a deviation from the usual manner of forming the hook member shown in Fig. 1 and allows the entire frame to be formed of a continuous piece of wire instead of being broken off above the twisted portion.

Instead of utilizing the usual horizontal base member formed of wire I prefer to substitute therefor the bar 6 which has elongated holes in each end thereof to receive the end portions of the wire frame 7 and 8 which are formed from the diverging shoulder portions 1 and 2. By using this type of a horizontal base member for the wire frame a more rounded edge is provided to prevent a crease from being formed when the trousers are placed thereon.

Referring now more particularly to Fig. 3, the cardboard covering itself is actually composed of front and back portions 9 and 10 respectively. The front portion 9 is provided at each side thereof with a plurality of corrugations or scores 11 and 12 diverging outwardly from the top edge to render this portion of the covering resilient so that it will tend to take on a rounded contour when any weight is applied to the top thereof such as when placing a coat thereon. At each side of the outer edge and at the top of the front 9 is provided a tab 13 which is adapted to be folded over the wire frame along the upper part of the scored portion 11 and 12. Adjacent the tabs 13 are two ears 14 which are adapted to be folded over the upper section of the diverging shoulder portions 1 and 2. Between the ears 14 is a tab 15 which may be considered as a reinforcing member. Another reinforcing member 16 is preferably placed along the scored portion immediately below the ears 14 and the tab 15 and is secured to the inside of the front 9 by means of glue or any other desired means.

There is a connecting portion 17 which is scored at each longitudinal side thereof and which connects the front 9 with the back 10 of the cardboard cover. Also on the back 9 are scored portions 18 and 19 which diverge from the top edge of the back portion 10. Adjacent the scored portions 18 and 19 are tabs 20 and 21 which are adapted to fold over the wire frame, within the front portion 9 of the covering. When the covering is in place and folded over the wire frame, the tabs 20 and 21 are actually within the tabs 13 and therefore may be termed inner tabs 55

whereas the tabs 13 may be designated as outer tabs.

In this construction I prefer to secure the various pieces together by means of an adhesive, but it is understood that it is within the scope of my invention to use any other desired form of securing means such as staples and the like. Before folding the covering over the frame an adhesive is placed on the areas denoted by the letters A 10 and B and on the ears 14 and the tab 15. The tab 15 is then folded over the reinforcing member 16 and secured thereto by means of the adhesive. The wire frame is then placed in the covering so that the diverging shoulder portions 15 1 and 2 lie against the scored portions 18 and 19 of the back while the horizontal base member 6 will be positioned underneath the connecting portion 17 as viewed in Fig. 3. The first operation then is to fold the tabs 20 and 21 over the diverging shoulder portions 1 and 2. With the tabs 20 20 and 21 in this position the entire back is then brought in contact with the front so that the tabs 20 and 21 will be secured to the front portion 9 by means of the adhesive in the sections B. The tabs 13 and the ears 14 are then folded over the back 10 so that the completed hanger will be then as viewed in Fig. 1.

It is to be noted that this construction will allow the covering to be moved vertically on the wire frame due to the openings 22 and 23. The covering must be raised in order to allow trousers to be placed on the horizontal base member 6, and when a coat is placed thereover the scored portions 11 and 12 will spread out to form a rounded surface on which the shoulder portions of the coat may rest. Also the weight of the coat will force the covering down so that the connect-

ing portion 17 will contact the trousers which have been placed on the member 6 thus maintaining them in position and preventing their slipping in either direction.

From the above explanation it will be seen that 5 I have constructed a garment hanger having novel features of construction, is durable, and exceedingly economical from a manufacturing standpoint.

Other modes of applying the principle of my 10 invention may be used instead of the one here explained change being made as regards the elements herein disclosed, provided however that the means stated by any of the following claims or the equivalent of such stated means be employed. 15

I claim:

1. A garment hanger comprising, a horizontal bar over which a garment is to be folded, a hanger structure attached to the opposite ends of said bar and extending upwardly in spaced relation 20 from said bar, a cover member to support a second garment, said cover member having sides disposed at opposite sides of said hanger structure and vertically slidably thereon, and a lower substantially rigid portion extending between the 25 lower edges of said sides and extending lengthwise the greater portion of the length of said bar and movable toward or away from said bar.

2. The elements in combination defined in 30 claim 1 in which said lower portion of the cover structure is formed integrally with the respective side portions thereof.

3. The elements in combination defined in 35 claim 1 in which said lower portion of the cover structure lies between said bar and said hanger structure.

WALTER HAROLD BATT.
